UNITED STATES PATENT OFFICE

JOSEPH P. MANNING, OF SAWTELLE, CALIFORNIA

COLLAR ATTACHMENT

Application filed April 26, 1930. Serial No. 447,677.

This invention relates to improvements in fastening devices, particularly a device or attachment for a collar by means of which the collar may be secured to the neck band of a shirt, the attachment replacing the usual collar button.

The primary object of the present invention is to provide a device designed to replace the collar button, the device being so formed that the usual hard protrusion formed by the collar button is done away with and the wearing of a collar with which the device is used is made more comfortable.

The present invention broadly contemplates the provision of a flat body of cloth material of relatively heavy weave to one face of which is attached a pair of relatively long tabs. The collar with which the attachment is to be used is modified slightly in its construction by providing at each side of the buttonhole in the back thereof and at each side of the buttonhole formed through one tab thereof a buttonhole through which the tabs of the attachment may be passed. The flat portion of the attachment is placed within the collar band and the two tabs are extended through the openings in the overlapped collar tabs after which the attachment tabs are folded back to each extend through an added opening in the collar tab to position one between the collar and the shirt band and the other between the collar tabs. The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

45 In the drawing:

Figure 1 is a horizontal sectional view through a collar and a shirt band to which the collar is attached, showing the application of the attachments embodying the present invention.

Figure 2 is a view in front elevation of a collar from which has been broken away part of the outer portion thereof overlying the collar tabs, showing the application of the present invention.

55 Figure 3 is a detailed perspective view of the invention per se.

Referring more particularly to the drawing wherein like numerals of reference indicate corresponding parts throughout the several views, the numeral 1 indicates generally the collar band of a shirt, the buttonholes through the front overlapping portions thereof being indicated by the numeral 2 and the buttonhole in the rear thereof being indicated by the numeral 3.

60 A collar attached to the band 1 is indicated generally by the numeral 4, the numeral 5 designating the inner fold of the collar while the outer fold is designated by the numeral 6. The tabs or terminal portions of the collar are indicated by the numerals 7 and 8, 7 indicating the inner tab and 8 the outer tab which in addition to being secured in place over the inner tab by the collar attachment about to be described, may also be held in position by the button 9 carried by the inner or under tab 7.

65 70 75 In addition to the usual buttonholes 10 formed through the collar tabs 7 and 8, the front tab 8 has formed upon each side of the buttonhole therein an extra buttonhole 11. This is also true of the rear portion of the collar where the usual buttonhole 12 is flanked on each side by an auxiliary buttonhole 13.

80 85 The collar attachment comprises a body 14 preferably of the rectangular design shown constructed of a heavy weight cloth of suitable character such for example as canvas. To one face of this rectangular body in the central portion thereof there is secured a pair of relatively long tabs 15, the ends attached to the body 14 being oppositely directed in the manner shown.

90 95 100 In use this body 14 is placed inside the shirt collar band and the tabs 15 are extended through the shirt band buttonhole and, when used in the front of the collar, are then extended through the usual buttonholes of the overlapped collar tabs 7 and 8.

The attachment tabs 15 are then turned to extend in opposite directions and each is passed through the adjacent aperture or hole 11 in the collar tab 8 so that, as is clearly shown in Figures 1 and 2, one of the attachment tabs extends to a position between the inner and outer folds of the collar while the other extends to a position between the inner fold of the collar and the shirt band. The application of the device to the rear of the collar and collar band will be readily apparent from the drawings and from the description of its application to the front of the collar.

From the foregoing it will be readily seen that by using an attachment of the character herein described for securing a collar in position on a collar band, in place of the usual stiff or hard collar button much greater comfort will be afforded the wearer of the collar than if a collar button of the usual type were employed.

Having thus described my invention, what I claim is:

1. The combination with a shirt collar band having button apertures therein and a collar having in addition to the usual collar buttonhole an aperture at each side of said hole, of an attachment to replace a collar button comprising a body, and a pair of flexible tabs attached thereto, said body when in use being disposed within the shirt collar band and having the tabs extended through the shirt band collar button opening and the collar buttonhole and each tab being turned and extended back through an aperture adjacent the collar buttonhole.

2. The combination with a shirt collar band having button apertures therein and a collar having the usual collar button aperture therethrough and having two additional apertures one at each side of the collar button aperture, of a collar button replacement device comprising a base of flexible material adapted to be positioned within the collar band, and a pair of flexible tabs carried by the base to extend through the collar button opening of the collar band and the collar button aperture of the collar, said tabs being turned laterally in opposite directions and each extended through one of said additional apertures.

3. In combination with a shirt collar band having button apertures therein and a collar having one of the front tabs thereof provided with an aperture at each side of the usual collar button opening, of a collar button replacement device comprising a flexible base body adapted to be positioned within the shirt band to which the collar is to be attached, and a pair of relatively long flexible tabs carried by the base body and extended through the shirt band and the usual apertures of the overlapping collar tabs and turned laterally in opposite directions, each

of the attachment tabs being threaded through an aperture in the collar tab to position one between the collar and the shirt band and the other between the folds of the collar.

In testimony whereof I hereunto affix my signature.

JOSEPH P. MANNING.
